UNITED STATES PATENT OFFICE

2,265,601

RECORDING STYLUS

Henry Louis Imelmann, Chicago, Ill., assignor to
Permo Products Corporation, Chicago, Ill., a
corporation of Illinois

Application December 30, 1940, Serial No. 372,298

2 Claims. (Cl. 274—38)

My invention relates to recording stylus, and is directed more particularly to a construction which affords the use of more efficient manufacturing equipment, resulting in an improved stylus and in one which is cheaper to manufacture.

One of the objects of my invention is to provide a stylus which may be manufactured by the use of more efficient grinding apparatus and grinding operations.

Another object of the invention is to provide a stylus construction which affords the use of a grinding lap of increased size whereby the necessary grinding is completed much more easily, accurately, and efficiently.

Other objects and advantages of the invention will become apparent from the following specification and accompanying drawing, in which:

Fig. 1 is a side elevation of the stylus as it is applied to the lap in a manner according to my invention;

Fig. 2 is a side elevation of a modified form of the completed stylus;

Fig. 3 is a front elevation showing the leading face of the stylus; and

Fig. 4 is a front end elevation of the stylus.

Referring to the drawing, particularly to Figs. 1 and 3, it will be seen that the stylus includes a body portion 10 having a flat 11 ground thereon to facilitate the alignment thereof in the recording machine. The forward end of the stylus is formed to provide a pair of angularly disposed rear faces 12—12 and a forwardly disposed leading face 13 terminating in a pair of cutting edges 14, which edges form the junction between the faces 12 and the face 13.

In manufacturing the stylus the principal operation is that during which the faces are ground to their proper proportions, the tolerance permitted in these proportions being extremely slight in order to insure that the groove cut by the needle is one of proper proportion. Generally speaking there are three grinding operations: the first, a rough cut whereby the general configuration is obtained; the second, a medium cut which constitutes a cut which carries the dimensions of the faces 12—12, 13 to the proper proportions; and third, the finishing operation during which a minimum of material is taken from the stylus and rather an extremely high polish is obtained. This last cut is for the purpose of sharpening the edges 14 to such a degree that a clean cut is obtained in the material being worked upon.

It will be readily understood that should a large lap be used to grind the leading face on the needle, it would be necessary, in order to ob-

tain the proper angle of the face 13 with respect to the longitudinal axis of the stylus, to cut away the shank material a considerable distance up the shank portion of the stylus. This results in a 5 weakening of the needle and has a serious detrimental effect on its mechanical properties. It has also been found in the past that with the use of a lap having a smaller circumference, the working spot thereon has considerable curvature due to the reduced diameter of the lap, and that under these conditions it is almost impossible to properly align the face of the stylus on the circumferential edge of the lap to avoid grinding merely a portion of the leading face during the 10 second and third operations, which face of course has been previously formed during the first grinding operation.

Another disadvantage in styli of the straight type is that in attempting to work them on a 15 large lap it has been found that the chuck or tool actually engages the circumferential edge thereof and disrupts the entire grinding operation.

In order therefore to utilize a larger lap and thereby gain the advantages first of an extremely 20 higher grinding surface speed, and second, a minimum of grinding away of the shank portion, the utilization of a relatively flat working spot due to increased diameter and increased circumference, and to be able to efficiently grip the shank and avoid wearing of the chuck against the circumferential edge of the lap, I have constructed a 25 stylus formed as shown in Figs. 1 and 2.

As will be seen from Fig. 1, all of the foregoing 30 difficulties are avoided by bending the stylus as at 15, whereby the shank is removed to a considerable degree from the working plane to permit the utilization of a larger lap.

From past experience it has been found that 35 when the smaller lap, made necessary by the straight shank, was used, considerable difficulty 40 was encountered in aligning the leading face 13 of a needle against the circumferential wall of a lap for the second and third operations. With the construction shown in Fig. 1, however, and 45 with the lap there shown, it is now found that the working spot on the lap, that is the area covered by the face 13 as it is being ground, is so small with respect to the enlarged curvature of the lap that this working spot has been effectively flattened out. Under these circumstances the worker has little or no difficulty in 50 aligning the stylus for the second and third operations, and as a matter of fact the alignment now amounts to merely placing the face against 55 the circumferential edge of the lap. With the

present construction the examination of a large amount of needles made in this way has revealed that the grinding on the second and third operations has covered the entire face 13, and there are no longer partial grindings wherein certain spots on the needle have been missed by the lap in the second and third grinding operations due to the extreme curvature of the working spot on the lap.

The modified form of stylus shown in Fig. 2 embodies the same principles heretofore described. However, the shank 10" is not integral with the stylus portion 17 upon which the faces 12"-12" and 13" are ground. The shank 10" has a longitudinal bore 18 therein, into which the portion 17 is placed, whereupon the shank is wedged as at 19 to retain the portion 17 within the shank. The portion 17 is similarly bent as at 20.

Having thus described my invention what I claim as new and desire to secure by United States Letters Patent is:

1. As a new article of manufacture, a recording stylus, said stylus having a shank portion for engaging in a recording instrument and a groove cutting portion at one end of said shank portion, said shank having a bend therein at a point intermediate the portion which engages in the recording instrument and the cutting portion, said cutting portion including a leading face all points of which are outside of a circumferential plane defined by said shank portion.

2. As a new article of manufacture, a stylus, said stylus having a shank portion for engaging in an instrument with which it is to be used and a portion having cutting means for engaging the material to be cut, said shank portion and said portion having the cutting means being disposed angularly to one another, said cutting means including a leading face all points of which are outside of a circumferential plane defined by said shank portion.

HENRY LOUIS IMELMANN.
